UNITED STATES PATENT OFFICE.

SAMUEL JASPER VANCE, OF CARTHAGE, MISSOURI.

RAIN-WATER FILTER.

SPECIFICATION forming part of Letters Patent No. 683,529, dated October 1, 1901.

Application filed January 17, 1901. Serial No. 43,650. (No model.)

To all whom it may concern:

Be it known that I, SAMUEL JASPER VANCE, a citizen of the United States, residing at Carthage, in the county of Jasper and State 5 of Missouri, have invented a new and useful Rain-Water Filter, of which the following is a specification.

This invention relates to filters in general, and more particularly to that class designed 10 for filtering rain-water before it passes to a cistern; and the object of the invention is to provide a construction wherein the water from the rain-spout will first pass to the sewer or other waste, after which it will be caused to 15 pass through the filter by automatic operation of a cut-off valve, and when the water has ceased to run to the filter the cut-off valve will be opened to permit the filter to drain.

20 Further objects and advantages relating to details of construction will be evident from the following description.

In the drawings forming a portion of this specification, and in which like numerals of 25 reference indicate similar parts in the several views, Figure 1 is a view showing the body of the filter in elevation with the inlet-pipe, the waste-pipe, and the valve-chamber in section. Fig. 2 is a view similar to Fig. 1 and showing the positions of the parts when 30 the cut-off valve has been operated to close the waste-pipe. Fig. 3 is a view similar to Fig. 1 and showing the cut-off or waste valve open to drain the filter when the water has 35 ceased to run into the apparatus, as when it has stopped raining. Fig. 4 is a vertical section taken through the filter-chamber and the waste-pipe and valve-chamber, the inlet-pipe being shown in elevation. Fig. 5 is a 40 transverse section through the apparatus just above the outlet of the cistern. Fig. 6 is a section on line 6 6 of Fig. 3.

Referring now to the drawings, the present 45 apparatus consists of a cylindrical filter-chamber, in one side of which and adjacent to the bottom is a waste or drain opening 11 and at a slightly-greater elevation an inlet-opening 12, the body or chamber 10 having also an outlet-opening 14 at a point near to 50 its upper end, provided with a spout 15. Connected with the opening 11 is a vertical pipe

16, extending above and below said opening, the upper portion of this pipe being divided off by means of a transverse partition 17 to form a float-chamber 18, while the lower portion of the pipe forms the waste for the filter-chamber. In the pipe 16 below the opening 11 is a valve-seat, with which co-operates a downwardly-opening valve 19, having a rod 20, which extends upwardly through the 60 valve-seat and through a perforation in the partition 17, above which latter is attached a float 21, whereby when the float-chamber is filled with water the float will be raised to raise the valve and close the waste-pipe. To 65 limit the downward movement of the valve, the rod 20 is provided with a flange 22 for engagement with the partition 17.

Connected with the opening 12 is the inlet or feed pipe 25, having a cylindrical upward 70 extension 26, and through which extension and feed-pipe the rain-water passes from the rain-spout 27 to the body of the filter. Through the side of the extension 26 leads a by-pass 28, the inner end of which is inclined and 75 has a perforated plate 29 in its end, and in connection with this plate is a pivoted closure 30, which is mounted upon the plate and has a handle 31 extending through the side of the extension 26 for operating it. By manipulating this handle the plate may be oscillated 80 to open and close the perforations. The outer end of the by-pass is passed through the cover 32 of the pipe 16, and thus as the rain passes down through the extension a portion of it 85 runs through the perforated plate and through the by-pass to fill the float-chamber. As it takes some time to fill the float-chamber, the water that first enters the body of the filter passes out through the waste-opening at the 90 bottom thereof, this water being charged with impurities from the roof of the building from which the spout leads and being thus of no value. When the float-chamber finally is filled, the float rises and cuts off the waste, 95 so that the water may pass upwardly through the filter and out through the outlet at the upper portion thereof. In passing upwardly through the filter-chamber the water passes 100 through a filtering-bed 35 of charcoal or other suitable filtering material and which is held in a foraminous basket 36, which snugly fits

- the chamber and rests upon brackets 37. To permit the water in the float-chamber to waste away, and thus permit the float to drop and open the waste-valve when the rain has ceased, 5 an opening 38 is formed in the sides of the float-chamber and near to the lower end thereof. With this construction it will be seen that when the rain-water first begins to flow into the filter-chamber the waste is open, 10 and as a consequence the water will pass directly to the waste, carrying with it the impurities that come down with the first water as washings from the roof. The inflow of water to the float-chamber is greater than 15 the outflow through opening 38, and hence the chamber fills and the float rises to close the cut-off or waste valve, when the water passes upwardly through the filter-chamber and through the filter-bed therein. When 20 the rain ceases, the water in the float-chamber wastes through the opening 38, and the float is permitted to sink and open the waste-valve to permit the filter-chamber to drain and carry off the impurities that are caught 25 by the filter-bed. The filter-bed may be removed and washed at any time or other filtering material may be substituted, as desired. In practice modifications may be made and any suitable materials and proportions may 30 be used. Furthermore, it will be noted that an overflow-pipe 39 connects the upper portion of the float-chamber with the inlet-pipe, which permits the water in the float-chamber to rise only to a sufficient height to operate the float, the excess of water being returned to the inlet-pipe to pass to the filter. Also a screen 40 is disposed in the extension 35 of the inlet-pipe above the by-pass to catch large pieces of foreign matter.
- 40 What is claimed is—
1. The combination with a filter-chamber, of a waste-pipe connected therewith, a valve for opening and closing the waste-pipe, a float-chamber, a float in the chamber and connected with said valve for operating it, an inlet-pipe connected with the filter-chamber independently of the float-chamber, a drain for the float-chamber and a by-pass connected with the inlet-pipe above its point of 45 connection with the filter-chamber and lead-
  - 50

ing to the valve-chamber to supply water thereto.

2. The combination with a filter-chamber of an inlet-pipe connected therewith, a waste-pipe connected with the chamber, a valve for 55 opening and closing the waste-pipe, a float-chamber, a float in the float-chamber connected with the valve for operating it, a by-pass connecting the inlet-pipe and the float-chamber for supplying water to the latter, 60 an overflow connecting the inlet-pipe and valve-chamber below the by-pass, and a drain for the valve-chamber.

3. The combination with a filter-chamber of an inlet-pipe connected therewith, a second pipe connected with the chamber and extending above and below its point of connection, said pipe having a transverse partition above said point of connection to form an upper float-chamber and a lower waste-pipe, 65 the latter having a valve-seat below the connection with the filter-chamber, a valve for said seat, a float in the float-chamber operatively connected with the valve, a drain for the float-chamber, and a by-pass between the 70 inlet-pipe and float-chamber.

4. The combination with a filter-chamber of an inlet-pipe connected therewith, a second pipe connected with the chamber and extending above and below its point of connection, said pipe having a transverse partition above said point of connection to form an upper float-chamber and a lower drain-pipe, 75 the latter having a valve-seat below said point of connection, a valve for said seat, a 80 float in the float-chamber and connected with the valve for operating it, a drain for the float-chamber, a by-pass between the inlet-pipe and the float-chamber above the water-line of the filter-chamber, a cut-off for said 85 by-pass, and an overflow between the float-chamber and the inlet-pipe.

In testimony that I claim the foregoing as my own I have hereto affixed my signature in the presence of two witnesses.

SAMUEL JASPER VANCE.
